(57) **CLAIM**

The ornamental design for a clinical analyzer with graphical user interface, as shown and described.

DESCRIPTION

This application contains subject matter related to the following co-pending U.S. design patent applications:

Application Ser. No. 29/627,767, filed herewith and entitled "Clinical Analyzer";

Application Ser. No. 29/627,777, filed herewith and entitled "Clinical Analyzer";

Application Ser. No. 29/627,778, filed herewith and entitled "Clinical Analyzer";

Application Ser. No. 29/627,780, filed herewith and entitled "Clinical Analyzer";

Application Ser. No. 29/627,764, filed herewith and entitled "Clinical Analyzer"; and

Application Ser. No. 29/627,774, filed herewith and entitled "Clinical Analyzer With Graphical User Interface".

The file of this patent contains at least one drawing executed in color. Copies of this patent with color drawings will be provided by the United States Patent and Trademark Office upon request and payment of the necessary fee.

FIG. 1 is a front elevational view of a clinical analyzer with graphical user interface according to the design;

FIG. 2 is a partial enlarged view of the display screen portion in FIG. 1; and,

FIG. 3 is a partial enlarged view of the claimed design portion in FIG. 2.

The broken lines showing the clinical analyzer are for illustrating environmental structure and form no part of the claimed design. The remaining broken lines depict elements of the graphical user interface that form no part of the claimed design.
